UNITED STATES PATENT OFFICE.

MATTHEW MORTON, OF MUSKEGON HEIGHTS, MICHIGAN.

TOOL-HOLDER AND MEANS FOR SETTING THE TOOLS THEREIN.

940,938.

Specification of Letters Patent. Patented Nov. 23, 1909.

Application filed May 28, 1908. Serial No. 435,552.

To all whom it may concern:

Be it known that I, MATTHEW MORTON, a citizen of the United States, residing at Muskegon Heights, in the county of Muskegon and State of Michigan, have invented 5 certain new and useful Improvements in Tool-Holders and Means for Setting the Tools Therein, of which the following is a specification.

10 My invention has for its object to provide an improved tool holder, and means for setting the tools therein, the same being adapted to be used on any ordinary planer or shaper and on various other machines of 15 analogous nature.

My invention is more especially designed for fitting brasses or boxes, as also shoes and wedges for connecting rods of locomotives, although I do not limit myself thereto, as 20 my invention contemplates, as coming within its scope, any use to which an improved tool holder may be applied. I have shown my invention as applied to the head of a cutter bar.

25 My invention consists of the construction, combination, and arrangement of devices and appliances hereinafter described and claimed and illustrated in the accompanying drawings, in which—

30 Figure 1. is a view in side elevation. Fig. 2. is a view in front elevation. Fig. 3. is an enlarged front view of the tool head with the clamping plate removed. Fig. 4. is a view in section on the line 4—4 Fig. 3 with 35 the crossing tools in place. Fig. 5. is a similar view with the longitudinal tool in place. Fig. 6. is a front elevation similar to Fig. 3. with the setting tool or gage in place. Fig. 7. is a view in section on the line 7—7 Fig. 6. Fig. 8. is a rear elevation of the mechanism shown in Fig. 6. Fig. 9. is a view in section on the line 9—9 Fig. 8.

I carry out my invention as follows: As 40 shown in the drawings my improved tool holder is constructed with a head 1 provided with an arm 2 to be engaged in any suitable cutter head 3. A cutter bar carrying the head 3 is indicated at 4.

Upon the head of the tool holder is 45 engaged a clamping plate 5. The head of the tool holder is constructed with recesses or grooves at 6 and 7 to receive corresponding tools 8 and 9, said recesses and tools being arranged on diagonal lines and crossing each 50 other as shown. The tools 8 and 9 when in place cross each other centrally of the tool

holder head, whereby said tools may project from the head at two opposite points, or at the opposite edges of the tool holder head. This construction enables the tools 8 and 9 60 to operate upon the opposite flanges of a piece of work indicated at 10. The tools 8 and 9 are held in the head of the tool holder by means of screws 11 and 12 clamping upon said tools. The clamping plate 65 itself is held upon the head of the tool holder by means of screws 13. It will be evident that the tools 8 and 9 can readily be removed or adjusted by loosening the corresponding screws 11 and 12. 70

To adapt the tool holder to receive a tool for other work, as for planing between the opposite flanges of a piece of work, the head of the tool holder is further constructed with a recess or groove 14 to receive a corresponding 75 tool 15 extending longitudinally of the holder, the tools 8 and 9 being removed when it is desired to employ the tool 15, the tool 15 being removed when it is desired to use the tools 8 and 9. The tool 15 is held in 80 place beneath the clamping plate by means of a set screw 16.

In order to readily set the tools 8 and 9 accurately and uniformly, I provide a setting device or gage consisting essentially of 85 a longitudinal arm 17, fitting into a recess 18 in the tool holder upon the opposite side of the tool holder head from the clamping plate 5, said arm being slotted as shown at 19 to pass astride a pin 20 engaged with 90 said head, said pin being provided with a hand nut 21 threaded upon said pin to clamp the arm 17 in place upon the head; the longitudinal arm 17 has a transverse arm 22 adjustably engaged therewith. The arm 17 is 95 preferably constructed with a transverse groove 23 to receive said transverse arm, said latter arm being constructed with an elongated slot 24 through which the transverse arm is held in engagement with the longitudinal arm by means of a set screw 25 provided with a thumb nut 26 threaded thereupon. The extremities of the transverse arm are constructed with elongated slots 27 and 28 through which adjustable stops or 100 angle plates 29 and 30 are engaged upon the transverse arm as by screws 31 and 32. The head of the tool holder is also provided with an adjustable stop 33. The longitudinal arm of the setting device or gage is provided with a shoulder or pin 34 to abut against said stop. By this means it will be 105 110

seen the setting implement may be readily applied in just the right position longitudinally of the tool holder to set the tools 8 and 9, after the stop 33 has been once properly adjusted. Said stop is shown constructed with an elongated slot 35, the same being held in place by means of a screw 36. I have shown the screw 20 provided with a spring 37 to keep a tension on the nut 21 so that it will not jar loose when the tool is taking its cut, a washer 38 intervening between the spring and the thumb nut.

The operation of the device will now be understood. By employing the setting instrument as described, the diagonal cutting tools 8 and 9 may readily be set in exactly the position desired and uniformly. By having the angle plates 29 and 30 of the setting implement adjustable it will be evident that the adjacent ends of the diagonal cutters may be set at any desired distance apart. One of the flanges of the adjustable angle plates 29 and 30 of the setting device are respectively shown, in Fig. 9, constructed with a projecting arm indicated at 40. Supposing it is desired to fit a box indicated at 10, in Figs. 1 and 2 for example, for the strap of a locomotive connecting rod. To set the tools in just the right position for making the necessary cut the arms 40 of the angle plates are adjusted against the opposite sides of the strap illustrated at 41, Fig. 9. This gives the exact distance across the strap which is the size of the groove which is to be cut in the box to receive the strap. When the tools 8 and 9 have been set correspondingly the work can be accurately carried on, without further trouble. No caliper is required, and, indeed, owing to one of the tools 8 and 9 lying on the other, it is impossible to caliper them with a pair of calipers, so that the setting device hereinbefore described is an absolutely essential feature of the tool holder, in order that the tools may be properly set, and the work be properly done. For the proper adjustment of the angle plates 29 and 30 the arm 22 is shown provided with a micrometer scale indicated at 42.

50 What I claim as my invention is:

1. A tool holder comprising a head constructed with oppositely extending diagonal grooves crossing each other intermediate their ends and arranged in different planes to receive and hold tools.

2. A tool holder comprising a head constructed with oppositely extending diagonal grooves crossing each other intermediate their ends and arranged in different planes, and a longitudinal groove crossing the diagonal grooves at the point of their intersection.

3. A tool holder comprising a head constructed with oppositely inclined diagonal grooves crossing each other intermediate

their ends and arranged in different planes with the adjacent sides of the grooves in the same plane, whereby a tool in one groove will engage a tool in the other groove at the crossing point of said grooves.

4. A tool holder comprising a head constructed with oppositely inclined diagonal grooves crossing each other intermediate their ends and arranged in different planes with one groove cutting into the other at their point of crossing, and a longitudinal groove in the plane of the other grooves and crossing said diagonal grooves at their intersection; and means at the intersection of said grooves to engage and hold a tool in any one of the grooves.

5. A tool holder comprising a head constructed with two diagonally extended grooves on different planes to receive corresponding tools, a clamping plate, means to secure the plate upon the head, and means to hold the tools in place, said diagonally extended grooves arranged on different planes whereby the corresponding cutters will overlap the one upon the other.

6. A tool holder comprising a head constructed with two oppositely inclined diagonally extending grooves arranged in different planes to receive tools, a clamping plate engaging one of the tools, means for securing the plate to the face of the head, and a set screw extending through said plate into engagement with one of the tools at the crossing point of said tools.

7. A tool holder comprising a head constructed with two oppositely inclined diagonally extending grooves arranged in different planes to receive tools to extend across the head, a set screw on the head to engage one of the tools at the point where it crosses the other tool, and set screws to extend into each groove near each end thereof to engage and hold the tools.

8. A tool holder comprising a rectangularly shaped head formed with a groove to receive a tool in one face extending diagonally across the same, and a similar groove within the head extending diagonally across in the opposite direction and in a plane at the inner side of the plane of the first groove, a plate secured to the face of the head over the groove therein, and set screws extending through the plate and head to engage tools in the grooves near each end of each groove.

9. In combination a tool holder comprising a head adapted to hold oppositely extending diagonally arranged tools, means for adjustably holding said tools from longitudinal movement, an arm detachably secured to the head, a transverse arm carried by said arm, and angle plates adjustably secured to the transverse arm to receive the ends of the tools within their angles.

10. The combination of a head provided

with means for receiving tools to extend diagonally in opposite directions, a pin on the head extending laterally therefrom, a slotted arm engaging the pin, means for adjustably 5 securing the arm to the pin, a transverse arm adjustably secured to the lower end of the arm on the head and provided with longitudinal slots, angle bars to engage the ends of the tools, and means extending through 10 the slots in the transverse arm to adjustably secure the angle bars thereto.

11. A tool holder comprising a head formed with oppositely extending diagonal grooves to receive tools, said grooves extending 15 in different planes, a plate secured to the head over the grooved side thereof, set screws extending through the plate to en-

gage and adjustably hold tools in said grooves, a longitudinally extending arm, means on the head for adjustably and detachably securing the arm to the head, a stop on the head against which said arm is adapted to be adjusted, a transverse arm on the lower end of the arm on the head, means for detachably securing the transverse arm to 25 the other arm, and means adjustable longitudinally on the transverse arm to engage the work and set the tools.

In testimony whereof I have signed this specification in presence of two witnesses. 30

MATTHEW MORTON.
